Primary Examiner — S. Bryan Reinholdt, Jr.*Assistant Examiner* — Andrew D Golson(74) *Attorney, Agent, or Firm* — PV IP PC; Wei Te Chung(57) **CLAIM**

The ornamental design for a booth, as shown and described.

DESCRIPTION

FIG. 1 is a front view of a booth showing our new design; FIG. 2 is a top view thereof; FIG. 3 is a right side view thereof; FIG. 4 is a left side view thereof; FIG. 5 is a back view thereof; FIG. 6 is a bottom view thereof; FIG. 7 is a perspective view thereof; and, FIG. 8 is a cross-section view along line **8-8** of FIG. 2. The broken lines in the drawings depict portions of the booth that form no part of the claimed design. The dot-dash broken lines in FIG. 2, FIG. 6, and FIG. 7 represent the bounds of the claimed design and form not part of the claimed design.
